Primary Examiner—Melvin B. Feifer

[57] CLAIM

The ornamental design for a doll's head, as shown and described.

DESCRIPTION

FIG. 1 is a front elevation of a doll's head showing my new design;

FIG. 2 is a front perspective of a doll's head showing my new design from the left of FIG. 1;

FIG. 3 is a side elevation of a doll's head showing my new design from the left of FIG. 2;

FIG. 4 is a front perspective of a doll's head with the eyes in a closed position, showing my new design from the right of FIG. 1; and,

FIG. 5 is a side elevation of a doll's head with the eyes in a closed position showing my new design from the right of FIG. 4.
